Atty.

GEORGE H. JOHNSON, OF BUFFALO, NEW YORK, ASSIGNOR TO HIMSELF AND GEORGE MILSOM, OF SAME PLACE.

Letters Patent No. 87,679, dated March 9, 1869.

IMPROVEMENT IN FIRE-PROOF GRANARY.

The Schedule referred to in these Letters Patent and making part of the same

To all whom it may concern:

Be it known that I, GEORGE H. JOHNSON, of Buffalo, in the county of Erie, and State of New York, have invented a new and useful Improvement in the Arrangement, Combination, and Construction of the Compartments of a Fire-Proof Elevator Grain-Warehouse; and I do hereby declare the following to be a full and exact description thereof, reference being had to the accompanying drawing, forming a part of this specification, in which a sectional plan view of my improved granary is given.

Within comparatively few years past, the necessity for large grain-warehouses at the principal commercial centres of the country, to store under one roof hundreds of thousands of bushels of grain, has led to the construction, in Chicago, St. Louis, Buffalo, New York, and other leading cities of the continent, of immense granaries, wherein grain is handled wholly by machinery, and which are technically known as "elevators."

These elevators are built to hold from two hundred thousand to one million bushels of grain. Interiorly, they are divided vertically into bins or garners, in order that portions of the grain may be withdrawn independently of the remainder. Hence, these "elevator"-granaries require not only immense strength in the walls, to resist the outward thrust and pressure of the vast bulk of grain, but the walls must also be so constructed as to be capable of sustaining and resisting an unequal distribution both of weight and direct thrust.

At first these elevators were constructed of wood, involving great danger of conflagration, and the consequent expenditure of large sums for insurance.

By a series of important inventions, I have, in part individually, and in part jointly with others, gradually perfected the construction of absolutely fire-proof and vermin-proof granaries, wherein grain may be stored with perfect safety, be readily handled, by machinery, in quantities which, in any given time, are fabulous, as compared with the old methods, and be sweetened and renovated, when damp or musty, so as to prevent all loss from heating, rot, or decay.

The principle adopted in my last and most perfect granary, previous to the invention hereinafter described, was that of building closely, side by side, tall cylinders of masonry, by preference of brick, of uniform diameters and large dimensions, each capable of holding hundreds of bushels of grain.

This manner of constructing my improved fire-proof granaries, although a vast improvement upon the old forms, involves an immense expense, and the necessity of reducing this expense has led to the invention of the improved form of granaries or elevators, which is the subject-matter of the present application.

The nature of my invention consists in dividing the interior or inner space of a granary or elevator-warehouse, enclosed exteriorly by rows of large cylinders, of uniform diameter, built in close contact, by means of transverse intersecting rows of similar cylinders, so as to leave intermediate polygonal bins, or compartments, (as illustrated in the drawing,) which shall in-

clude all the space not occupied by the cylinders, and which shall have arched sides formed by their walls. I thus obtain, as I believe, a maximum of strength to resist the pressure of grain upon the walls of the structure, with the largest possible amount of space for the storage of the grain.

By making the walls of the structure hollow throughout, and converting the hollow spaces within the walls into ventilating cold or hot-air flues, the grain in all the compartments may be thoroughly ventilated, the inwardly-projecting arched sides of the intermediate polygonal compartments presenting, in proportion, nearly as much absorbing, ventilating wall-surface to the grain therein as in the smaller circular grain-spaces within the cylinders.

I form the outer walls of my granary, as usual, of a series of cylinders, A, of equal diameters, built in contact, side by side, including always, however, an odd number of cylinders (as three, five, seven, &c.,) between the cylinders at and constituting the corners of the structure.

In combination with said outer cylinders, parallel thereto, and within the space enclosed thereby, I erect, in contact, a row of cylinders, A', of the same diameter, extending from every alternate cylinder in the outer tier, across the inner space, so as to intersect therein.

Thus, within said interior space of the structure, the space B, included between any four of the cylindrical bins in contact, is left vacant, and these spaces B are fitted for the storage of grain, in common with the cylinders themselves.

It is evident that each space or compartment B, thus provided in the granary, will contain four times the amount of grain which can be placed in any one cylinder A, whilst the amount of wall-surface through which ventilation may be secured, is increased in the same proportion. At the same time, the outward pressure, from the grain contained therein, is brought to bear upon the crown of the series of arches formed by the cylinders constituting its walls, so that these compartments will sustain far more pressure from within than can be safely brought to bear upon the simple cylinders. It is also evident that, when full, they will strengthen and support the adjacent cylinders.

Having thus fully described my invention, I claim as new, and desire to secure by Letters Patent—

A granary, enclosed by a row of outer cylinders, or cylindrical compartments, and divided interiorly by transverse intersecting rows of contiguous cylinders, so as to form intermediate polygonal compartments, substantially as herein described and illustrated.

The foregoing specification of my improvement in the combination and arrangement of the compartments of a fire-proof granary, signed by me, this 14th day of January, 1869.

GEO. H. JOHNSON.
